UNITED STATES PATENT OFFICE

WILLIAM GARDNER, OF LONDON, ENGLAND.

BREECH-LOADER.

SPECIFICATION forming part of Letters Patent No. 281,862, dated July 24, 1883.

Application filed February 3, 1883. (No model.) Patented in Germany November 1, 1882; in France November 13, 1882; in England November 22, 1882, No. 5,556, and in Austria November 28, 1882.

To all whom it may concern:

Be it known that I, WILLIAM GARDNER, of London, England, have invented new and useful Improvements in Breech-Loading Guns, (for which I have obtained a patent in Great Britain, No. 5,556, bearing date November 22, 1882; also a patent applied for in Germany November 1, 1882; a patent applied for in France November 13, 1882, and a patent applied for in Austria November 28, 1882,) of which the following is a specification, reference being had to the accompanying drawings.

This invention relates to improvements in breech-loading guns, and is designed to provide means for insuring the highest possible speed in firing.

Figure 1 of the accompanying drawings represents the gun in longitudinal vertical section with breech-bolt being advanced. Fig. 2 is a longitudinal vertical section of the same, showing the breech-bolt drawn back. Fig. 3 is a part longitudinal horizontal section of the same. Fig. 4 is a rear view. Fig. 5 is a section at A B, Fig. 2. Fig. 6 is a section at C D, Fig. 3. Figs. 7, 8, 9, and 10 are details.

The gun consists of four principal parts—the barrel A, the receiver B, the breech-bolt C, and the cartridge-feeder D. The rifled barrel contains in its rear part the cartridge-chamber a, which is tightly screwed into the receiver. The receiver is of peculiar shape. The fore part, into which the barrel is screwed, is round and carries the trunnions. The rear part is also round. Both the said round parts are connected by two parallel bars, b and b', Fig. 5.

In the rear round part of the receiver is pivoted on the pin e the cartridge-feeder D, Figs. 1, 2, and 5. This feeder is provided with a hook, d, at the top and with a projection, f, at the bottom. The shape of both exactly corresponds to the diameter of the head of the cartridge. The cartridge is inserted by hand into the feeder. When the breech-bolt C is pushed forward, the roller g of the feeder rests upon it, and when the breech-bolt is drawn back the feeder drops as far as the stop h in the receiver permits, and thereby allows the cartridge to fall between the two bars b b'.

The space between the bars is equal to the 50 largest diameter of the cartridge-body; but the bars are rounded out according to the diameter of the head of the cartridge in line with the axis of the bore. The groove i, Figs. 2 and 5, in both bars enables the cartridge to fall 55 until the axis of the projectile is in line with the axis of the bore. By pushing forward the breech-bolt the feeder is again lifted until it occupies its former position upon the breech-bolt, and the cartridge is pushed forward into 60 the cartridge-chamber of the barrel. After a shot has been fired the empty cartridge-case, on withdrawing the breech-bolt, is drawn back by the extractor E until it reaches the grooves k, Figs. 2 and 5, of the two bars b b'. Here 65 the flanged head of the cartridge loses its support and the cartridge-case falls out of the receiver, while, by reason of the feeder D falling at the same time, a fresh cartridge is fed into the receiver. 70

The extractor E, Figs. 3 and 9, has a lug, l, which lies in the groove of the breech-bolt. It is provided on its fore end with the hook n, and is pressed against the periphery of the breech-bolt by the spring o, so as to engage 75 with the head or flange of the cartridge-case. The extractor is pivoted at the end l, so as to allow the hook n an outward movement equal to the width of the flange of the cartridge-case, and the extractor and spring are guided 80 in a groove, p, of the receiver, Figs. 2 and 3. The operation of the extractor can be clearly seen from the drawings.

The breech-bolt C forms the breech-closure of the barrel. For this purpose it is provided 85 with the screw-thread q. The corresponding female screw-thread is situated in the box r, in the rear round part of the receiver B, Figs. 1, 2, 3, and 6. The screw-thread in the receiver, and also that on the breech-bolt, is cut away, 90 as shown in Figs. 2, 3, 6, and 9, in order to enable the pushing forward and drawing backward of the breech-bolt in the receiver. A sixth of a turn then effects the closure. For the effectual guidance of the breech-bolt within the receiver the screw s is provided, which enters in a corresponding groove, t, of the breech-bolt, Fig. 10. The turning of the breech-bolt

in order to execute the closure of the breech is effected by the handles F and the screws u' and u'' , that are screwed into the hub of the handles. By turning the handles the cocking of the firing-pin G, lying within the breech-bolt, is effected in the following manner—that is to say: Upon the firing-pin is screwed the guide-piece v. This latter passes through a slot, v', forming a rectangle in the side of the breech-bolt, and is guided in the extractor-groove p, and is thereby prevented from turning. The spiral spring w presses the firing-pin forward. The rear end of the firing-pin extends through the bottom x of the handle-hub, and is provided with the two pins y and y', standing opposite each other. On the bottom piece, x, is fixed a cam-piece, z, which has two inclined planes, z' and z'', Figs. 1, 3, 7, and 8. By a third of a turn of the handles F, or of the cam-piece z, both pins y and y' are brought upon the inclined planes z' and z'', and the trigger-slide b'', always pressed upward by the spring a', can catch in the notch j of the firing-pin, thereby retaining it in the cocked position. The two screws u' and u'' , which are screwed in the hub of the handle F, and on the turning of the handle effect the moving of the breech-bolt, extend with their points into two grooves, d' d'', on the periphery of the breech-bolt, Figs. 1 and 8. These grooves are of such length that the screws u' and u'' only reach the ends of the grooves after a third of a turn of the handle, and then only after a further sixth of a turn move the breech-bolt along with them and thereby open the breech. The trigger-slide b'' is moved downward by a pressure of the hand, thereby the cocked firing-pin becomes free, springs forward, and explodes the cartridge. The succession of the operations above described is as follows—that is to say: The gun is loaded, the breech-bolt pushed forward, the firing-pin cocked, and the feeder provided with a cartridge. Pressure is placed upon the trigger-slide, thereby releasing the firing-pin and firing the cartridge. A third of a turn to the left is given to the handle, whereby the firing-pin is again cocked. A further sixth of a turn is given to the handle, (so that the said handle now has made a half-turn in all,) thereby loosening the closure of the breech-bolt. The breech-bolt is drawn back, at the same time retracting the empty cartridge-case and inserting a fresh cartridge by the feeder in the receiver. The breech-bolt is pushed forward, thereby inserting the cartridge into the cartridge-chamber of the barrel. Half a turn to the right is given to the handle, thereby effecting the closure and the insertion of a fresh cartridge into the feeder.

What I claim is—

1. In a breech-loading gun, the combination, with the receiver composed of front and rear portions joined by separated bars, of a cartridge-feeder located on top of the rear portion

of the receiver and adapted to swing down between the bars to insert the cartridge therein in line with the barrel, substantially as described.

2. In a breech-loading gun, the combination, with the receiver composed of front and rear portions joined by separated bars, of a cartridge-feeder pivoted at one end directly to the top of the rear portion of the receiver, and having its free end arranged to swing down between the bars to introduce the cartridge between the same, and a longitudinal movable breech-bolt which elevates the feeder when advanced and permits the feeder to drop when retracted, substantially as described.

3. In a breech-loading gun, the combination, with the receiver composed of front and rear portions joined by separated bars, of a cartridge-feeder having its rear end pivoted on the top of the rear portion of the receiver and its forward free end provided with a roller and a hook and projection, said free end being adapted to swing down between the bars to introduce the cartridge between the same, and a longitudinally-movable breech-bolt provided with a firing-pin which extends through the rear end of the bolt, substantially as and for the purpose described.

4. The combination, with the receiver B, having a longitudinal groove, p, of the longitudinally-movable breech-bolt C, constructed with the exterior groove, t, and the right-angled slot v' v' at or near the center of its length, the spring-impelled firing-pin G, having a guide-piece, v, projecting through the right-angled slot of the bolt into the groove of the receiver, and a pin, S, secured to the receiver and adapted to the groove in the bolt, substantially as described.

5. The combination, with the receiver B and barrel A, of the longitudinally-sliding and rotating breech-bolt C, provided at its rear end with grooves d' d'', a longitudinally-movable firing-pin located in the breech-bolt, a hub arranged over the end of the breech-bolt and provided with a handle by which to rotate it, and pins or screws u' u'' , secured to the hub and extending into the grooves at the rear end of the breech-bolt, and means connecting the hub with the firing-pin for cocking the latter, substantially as described.

6. The combination, with the receiver B and attached barrel A, of the breech-bolt C, provided at its rear with a rotating hub having a handle, F, trigger-slide b'', and interiorly provided with inclines z' z'', and the firing-pin G, having at its rear end the lateral pins y y' and notch j, substantially as described.

In testimony whereof I have hereunto signed my name in the presence of two subscribing witnesses.

WILLIAM GARDNER.
